CATALYSIS OF HYDROCARBONS

Filed March 27, 1943

UNITED STATES PATENT OFFICE

2,432,505

CATALYSIS OF HYDROCARBONS

Robert E. Burk and Everett C. Hughes, Cleveland Heights, Ohio, assignors to The Standard Oil Company, Cleveland Ohio, a corporation of Ohio

Application March 27, 1943, Serial No. 480,804

9 Claims. (Cl. 260—683.4)

1

This invention relates to the catalytic treatment of hydrocarbons to produce branched-chain hydrocarbons in the gasoline boiling range, such as iso-pentane, iso-octane, neo-hexane, 2,3-dimethyl butane, etc., which may be used as aviation gasoline base stock, with lead tetraethyl, or blended in ratios other than those of normal recovery.

It has been proposed heretofore to alkylate iso-paraffins with olefins by a number of different processes. But the iso-paraffins of the desired molecular weight used in such processes do not occur normally in liberal amounts and must be formed from normal hydrocarbons by a separate and different process before they can be alkylated.

In accordance with this invention it is possible to produce alkylation products of the desired configuration and boiling range from a wide variety of hydrocarbon raw materials and in a unitary process using a single catalytic material that is readily recoverable and reusable.

It is an object of the invention to provide a unitary process of producing branched-chain hydrocarbons in the gasoline boiling range utilizing hydrogen fluoride as the catalyst promoted by a minor amount of boron trifluoride as the essential catalytic agent for forming the iso-paraffins and for alkylating them with olefins.

A further object of the invention is to provide a process in which the same above described catalytic material is not deleteriously affected by the process and may be recovered and recycled through the various stages of the process indefinitely.

An additional object of the invention is to provide a process in which either normally gaseous and normally liquid hydrocarbons, and particularly both of them, may be used as the raw materials.

Still a further object of the invention is the provision of a process in which substantially all of the initial products are eventually converted into the wanted branched-chain products and in which those initial products not so converted in the first pass are recycled further and converted.

In practicing the invention a normally gaseous hydrocarbon, preferably high in butanes; or a higher boiling fraction, such as a C₆ cut or preferably a fraction boiling above 300° F. such as kerosene or gas oil; or preferably a mixture of both, is treated with hydrogen fluoride and a minor amount of boron trifluoride under appropriate conditions to accomplish averaging, cracking,

2

isomerizing, and possibly some alkylating. The mixture is then treated to separate the hydrocarbons formed as a result of the reactions referred to, from the major portion of the catalyst and the materials which are associated with it. The catalyst is returned to the reaction zone.

The separated hydrocarbons contain butanes, a major portion being iso-butane, and hydrocarbons of higher molecular weight. Depending on the composition of the feed, there may be some hydrocarbons of lower molecular weight than butanes. Some of the catalyst, including both hydrogen fluoride and boron trifluoride, may remain with the separated hydrocarbons.

15 The separated hydrocarbons are then fractionated to yield a C₄ fraction containing the hydrogen fluoride and a smaller amount of boron trifluoride dissolved therein. The major portion of the butane fraction will be isobutane. The higher boiling hydrocarbons, preferably those not comprised in the wanted product, may be returned to the reaction zone where they are further treated with the feed stock and subjected to such reactions as cracking and averaging.

20 25 The lighter boiling hydrocarbons, if any, also may be included in the C₄ fraction, or they may be returned to the reaction zone, or otherwise disposed of.

The iso-butane containing fraction along with 30 some fluorides is then passed continuously to an alkylation zone and reacted with an olefin. The fluorides carried with the iso-butane fraction serve as the catalyst, but they may be supplemented by an additional supply, particularly of 35 hydrogen fluoride.

The products from the alkylation zone are then fractionated and the wanted branched-chain products may be separated on intermediate plates of the fractionator. The lighter products, 40 such as butanes and any lighter boiling products and including the catalyst, as well as heavier products, are separately returned to the reaction zone for further averaging, isomerizing and cracking reactions. A substantial part of the catalyst as well as the butanes may be recycled 45 to the alkylation zone, if desired. The C₅ and heavier hydrocarbons from the first fractionator may be passed through the second fractionator during a part or all of the process before being 50 returned to the reaction zone, so as to separate the wanted products that are formed initially in the reaction zone.

The invention will be understood in connection with the following example, given merely as illustrative, and in which reference is made to the 55

accompanying sheet of drawings showing schematically the manner in which the illustrative process may be practiced.

The raw materials preferably comprise a normally gaseous hydrocarbon which is fed into the process at 1, and a normally liquid hydrocarbon which is introduced at 2. By means of valves 3 and the conduit 4, both the normally liquid and normally gaseous hydrocarbons may be introduced through the same or different inlets at either end or at the center of the reaction zone 5 which is in the form of a mixer.

The normally gaseous hydrocarbon fraction preferred is butane which may contain some iso-butane. Some pentanes, particularly iso-pentane may be included and under some conditions, depending on the reaction to be effected in the reaction zone, this fraction may contain some propane, ethane, methane or mixture of any of them with each other or with the other gaseous hydrocarbons. Refinery gases containing butanes may be used to advantage and any olefins present in the gaseous fraction need not be removed before feeding it into the reaction zone. The normally gaseous hydrocarbon fraction may be under pressure so that a part or all of it is liquid at the time it is fed to the reaction zone.

The normally liquid hydrocarbon fraction may contain C₆ and higher hydrocarbons; preferably it has a boiling point above 300° F., but may include gasoline, heavy naphtha, kerosene, gas oil, reduced crudes, crudes, etc. When aromatics are present in the liquid fraction they may be removed preliminarily by any suitable process, such as by selective solvent extraction, or by removal through reaction with the hydrogen fluoride-boron trifluoride catalyst. Alternatively, the stock may contain aromatics if sufficient catalyst is present in the reaction zone and if the conditions of the reaction are otherwise suitable. Unsaturates may be contained in the liquid as well as the gaseous fraction fed to the reaction zone.

Present in the reaction 5 also is the catalyst comprising hydrogen fluoride in which boron trifluoride is dissolved. The temperature of the reaction may vary from -22 to +392° F., preferably from about 32° F. to 150° F. The pressure is such as to keep the hydrogen fluoride liquid at the temperature used, but may be any higher pressure than this if desired. The amount of hydrogen fluoride may be 5 to 300 volume percent, based on the hydrocarbons (as liquids), preferably 50 to 150 volume percent. The amount of boron trifluorides may vary from a trace to 50 mol percent, based on the amount of hydrogen fluoride. It is convenient to control and measure the amount of boron trifluoride in terms of its partial pressure. The partial pressure may vary from 1 to 600, preferably 25 to 300, pounds per square inch. The amount of boron trifluoride (based on the amount of hydrogen fluoride) corresponding to a given partial pressure will depend on the total pressure and the temperature. However, the boron trifluoride (B. P. -150° F.) present at any temperatures of the reaction will exert a partial pressure and because of the convenience of measurement and control it is preferred to express the amount of boron trifluoride in terms of partial pressure. The partial pressure within the range mentioned does not exceed the upper limit of 50 mol percent, based on the amount of hydrogen fluoride.

The length of the reaction may vary depending on the materials used, the products wanted, the

amount of catalyst, temperature, etc. The reaction time may involve a few minutes up to ten hours. The materials in the reaction zone are kept under agitation or otherwise in a state of intimate admixture. The operation may be batch or continuous and suitable apparatus to effect the same will be apparent to one skilled in the art from a consideration of this description. During the reaction boron trifluoride or hydrogen fluoride may be added from the reserve supply 6, through the valve 7 and pipe 8. If desired the hydrogen fluoride and boron trifluoride may be admitted separately from independent supplies. The separate supply of boron trifluoride may be used to maintain the desired partial pressure of boron trifluoride.

During this phase of the process the hydrocarbons will undergo isomerizing, averaging, cracking and possibly some alkylating depending on the composition of the feed stocks, and the conditions of the reaction. For example, a major part of the butane may be isomerized to iso-butane; lower and higher hydrocarbons may be averaged, i. e., a molecule of a lower molecular weight hydrocarbon and a molecule of higher molecular weight hydrocarbon may form two molecules of an intermediate molecular weight hydrocarbon which may then be isomerized or otherwise reacted; higher boiling hydrocarbons may be cracked and the cracked products may be isomerized, averaged or further cracked. If either feed stock contains unsaturates, alkylation of iso-paraffins or any aromatics present may take place.

After the reaction is complete the mixture is withdrawn through a conduit 9 and introduced into a settling tank 10 where the mixture will stratify into two layers.

The bottom layer contains the major portion of the catalyst and some hydrocarbons, generally unsaturates and aromatics which form a complex with the catalyst. The bottom layer may be withdrawn through a conduit 11 and passed to a separator 12 where the catalyst may be separated by heating and returned to the reaction zone through the pipe 13, or to a later stage of the process through the pipe 37. This action may be controlled by valves 15 and 16. The products remaining after the removal of the catalyst may be treated to separate any fraction, such as aromatics, if desired. In general these products comprise unsaturates which possess properties similar to a good drying oil.

The top layer, which contains iso-butane and higher and any lower boiling hydrocarbons, depending on the initial reactants and the reaction conditions, and some of the catalyst, is passed through a conduit 17 to a fractionator 18. The operation of the fractionator may be varied. In any event the C₄ fraction containing a major portion of iso-butane and some normal butane is separated and sent through the conduit 19. If lower boiling products are separately fractionated, they may be returned through the conduit 20, valve 21 and conduit 22 to the initial feed, or through conduit 23 and valves 24 and 25 and drawn off. Under some circumstances it may be unnecessary or undesirable to separate the light boiling hydrocarbons from the butanes since the former will be returned to the reaction zone at any event later in the process. In such a variation, the valve 26 may be closed and the fractionator operated to take the butanes and all lighter products through conduits 20 and 23, valve 24 and conduit 19.

The products boiling higher than the butanes are withdrawn from the fractionator through the conduit 27 and may be returned to the reaction zone through the conduits 28 and 29. Alternately, they may be sent through the conduit 30 for further fractionation. Valves 31 and 32 may be used to control the flow of these products.

The following specific example is illustrative of this phase of the process:

One volume of dearomatized kerosene derived from Pennsylvania crude, and two volumes of butane containing 16% iso-butane, are fed into the reaction mixer 5 initially. These are treated with one volume of liquid hydrogen fluoride and boron trifluoride in an amount to provide a partial pressure of 150 pounds per square inch, this amount being 0.534 part of boron trifluoride for each part of kerosene. The reaction was permitted to proceed for two hours at a total pressure of 210 pounds per square inch and at a temperature of 90° F.

Following this, the reaction mixture was stratified in the settling tank 10. The lower layer was found to obtain 7.15% of the hydrocarbons fed to the reaction zone. The upper layer contained 37.2% iso-butane, 20% n-butane, 27.75% boiling within the range of 70°-410° F., 6.15% boiling above 410° F., and 1.75% propane.

The iso- and normal-butane, comprising about 57% of the initial feed, may be fractionated and sent through the conduit 19 for alkylation. In this instance, in view of the small amount of propane formed, the propane may be sent with the butane fraction, which may be withdrawn from the fractionator through the conduits 20 and 23, valve 24 and conduit 18. The heavier fraction, comprising about 34% initial feed, is returned through the conduit 27 for further reaction, or through the conduit 30 to the fractionator 39.

It will be apparent that the above results may be considered only illustrative, since the character of the reacting ingredients constantly changes because of the stock to be recycled. This will eventually reach a substantial equilibrium, however, to provide good yields of iso-butane.

The iso-butane containing fraction is then passed through the conduit 19 to an alkylation zone 33 and an olefin also is admitted. The olefin can be introduced with advantage through the conduit 34 into the conduit 19 to become premixed with the iso-butane fraction. The iso-butane also may be used to extract the olefin from a gas in which olefin is contained. The iso-butane fraction carries with it a small amount of hydrogen fluoride and probably some boron trifluoride and these may be enough to effect the alkylation. Generally the amount of boron trifluoride is sufficient. Some alkylation reactions will proceed with hydrogen fluoride without boron trifluoride, but a small amount facilitates them. In other alkylation reactions the presence of boron trifluoride is essential. Thus it is not essential in all instances that boron trifluoride be contained in the iso-butane fraction. An additional amount of hydrogen fluoride may be admitted from the reserve supply 35 through valve 36 and conduit 37. Also some of the catalyst from the separator 12 may be admitted through the valve 16 and conduit 37. Alternatively a part or all of the catalyst containing lower layer can be introduced into the alkylating step through the valve 11a and conduit 11b without separation of the catalyst from the hydrocarbons.

The olefin admitted to the alkylation stage at 34 preferably is ethylene, propylene or butylene.

The iso-butane should be present in an amount of 2 to 15 mol per mol of olefin to insure the complete reaction of the olefin and to repress polymerization of the olefin. The unreacted iso-butane is simply recycled.

The alkylation operation is carried out under about the same temperature and pressure conditions as in the reaction zone.

The products from the alkylation zone are then 10 removed through a conduit 38 and fractionated at 39. The wanted products are withdrawn through the valves 40 and conduit 41 and sent to storage 42.

The hydrocarbons and the fluoride catalyst 15 may be separated and only the hydrocarbons fed to the fractionator 39. The fluoride catalyst may be recycled to the alkylation step or part of it may be carried to the reaction zone 5.

The butanes in the fraction in the conduit 19 20 (and any lighter boiling hydrocarbons) which are not alkylated, are returned through conduit 43 to the initial supply 4, or through the valve 43a and conduit 43b to the alkylation reaction. The fractionator is so operated that all of the hydrogen fluoride and boron trifluoride is returned with 25 this lighter fraction to the reaction or alkylation zone, because the fluorides boil at a lower temperature than that of the wanted products. The heavier products, boiling higher than those 30 of the wanted products, are returned through conduits 44 and 29 to be added to the heavier feed stock. As illustrative of this phase of the process, the following example is given:

The butane fraction introduced in the alkylation zone 33 through the conduit 19 is alkylated 35 with ethylene. The molal ratio of iso-butane to ethylene is 12:1. The excess of the iso-butane is returned through the conduit 43 and recycled. The alkylation reaction was carried out at a temperature of 34° F., in the presence of 11.4% by weight of boron trifluoride, and 18.7% by weight hydrogen fluoride based on the total hydrocarbons. The reaction time was 9 minutes. The products of the alkylation (based on the amount 40 of ethylene used which gives a theoretical yield of 307%) were iso-pentane, 24%; neo-hexane, 31.8%; 2,3-dimethyl butane, 93%; higher boiling hydrocarbons 43%; which are withdrawn through the conduit 41. The hydrocarbons boiling above 300° or 400° F. are returned through the conduit 44; these amount to but a very small part 50 of the hydrocarbons boiling above 2,3-dimethyl butane.

It will be understood that the description of 55 the invention is illustrative of a process, and that the drawing is to facilitate an understanding of the process. It is not intended to show apparatus that is suitable and no attempt is made to include heaters, condensers, pumps, etc., as these will be apparent to one skilled in the art in view of the description of the process herein.

In the above process, if the amount of gases, such as methane or ethane builds up in the system to a point where it is more efficient to remove 60 them rather than recycle them, they may be withdrawn through the valve 25 at any time. Since they may contain a part of the catalyst, it may be desirable to recover this by means of an absorption and desorption system, before using 70 the gases as fuel or for any other purpose.

Similarly the heavier product exiting from 44 may be fractionated to remove any products that are not to be returned to the reaction zone 5. The operations in this regard will depend on the 75 raw materials available and the efficiency re-

quired and economic factors. Generally, however, it will be seen that all of the products are converted to the branched-chain products of the desired molecular weight. By continuously removing them from the reaction zone, and by continuously removing the iso-butane and other isoparaffins by the alkylation process, the equilibrium is shifted in such a way as to be able to convert the great portion of the raw materials to the wanted products upon suitable recycling. This is made possible because of the unique characteristics of the catalyst employed.

The invention is capable of many detailed modifications, as will be apparent to one skilled in the art, and we intend all of such modifications to be included as are within the scope of our claims.

We claim:

1. A process of producing hydrocarbons in the gasoline boiling range by processes of averaging and alkylating, which comprises subjecting a mixture of a normally liquid hydrocarbon fraction and a normally gaseous hydrocarbon fraction containing a normal hydrocarbon to the action of a liquid catalyst comprising liquid hydrogen fluoride in which is dissolved not over 50 mol per cent of boron trifluoride (based on the hydrogen fluoride), and continuing the reaction under averaging conditions including a pressure to maintain the hydrogen fluoride liquid and at a temperature and for a period of time while adjusting the partial pressure of the boron trifluoride to produce averaged hydrocarbons intermediate said normally gaseous and said normally liquid hydrocarbon fractions and also to isomerize the normal hydrocarbon contained in said normally gaseous hydrocarbon fraction, separating said isomerized hydrocarbon, transferring said isomerized hydrocarbon to an alkylation zone together with the fluorides which separate therewith from the averaging reaction, alkylating at least part thereof with an olefin in the presence of the above-defined catalyst comprising said fluorides separated from the averaging reaction.

2. A process of producing hydrocarbons in the gasoline boiling range by processes of averaging and alkylating, which comprises subjecting a mixture of a normally liquid hydrocarbon fraction and a normally gaseous hydrocarbon fraction containing a normal hydrocarbon to the action of a liquid catalyst comprising liquid hydrogen fluoride in which is dissolved not over 50 mol per cent of boron trifluoride (based on the hydrogen fluoride), and continuing the reaction under averaging conditions including a pressure to maintain the hydrogen fluoride liquid and at a temperature and for a period of time while adjusting the partial pressure of the boron trifluoride to produce averaged hydrocarbons intermediate said normally gaseous and said normally liquid hydrocarbon fractions and also to isomerize the normal hydrocarbon contained in said normally gaseous hydrocarbon fraction, separating said isomerized hydrocarbon, transferring said isomerized hydrocarbon to an alkylation zone together with the fluorides which separate therewith from the averaging reaction, alkylating at least part thereof with an olefin in the presence of the above-defined catalyst comprising said fluorides separated from the averaging reaction, and separating said intermediate hydrocarbons and said alkylate in a single fractionating operation.

3. A process of producing hydrocarbons in the gasoline boiling range by processes of averaging and alkylating, which comprises subjecting a

5 mixture of a normally liquid hydrocarbon fraction boiling in the gasoline-kerosene range, and a normally gaseous hydrocarbon fraction containing normal butane, to the action of a liquid catalyst comprising liquid hydrogen fluoride in which is dissolved not over 50 mol per cent of boron trifluoride (based on the hydrogen fluoride), and continuing the reaction under averaging conditions including a pressure to maintain the hydrogen fluoride liquid and at a temperature and for a period of time while adjusting the partial pressure of the boron trifluoride to produce averaged hydrocarbons intermediate said normally gaseous and said normally liquid hydrocarbon fractions and also to isomerize the normal butane contained in said normally gaseous hydrocarbon fraction, separating said iso-butane, transferring said iso-butane to an alkylation zone together with the fluorides separated therewith from the averaging reaction, alkylating at least a part thereof with an olefin in the presence of the same above-identified catalyst comprising said fluorides separated from the averaging reaction.

4. A process of producing hydrocarbons in the gasoline boiling range by processes of averaging and alkylating, which comprises subjecting a mixture of a normally liquid hydrocarbon fraction boiling in the gasoline-kerosene range, and a butane fraction containing normal butane, to the action of a liquid catalyst comprising liquid hydrogen fluoride in which is dissolved not over 50 mol per cent of boron trifluoride (based on the hydrogen fluoride), and continuing the reaction under averaging conditions including a pressure to maintain the hydrogen fluoride liquid and at a temperature and for a period of time while adjusting the partial pressure of the boron trifluoride to produce averaged hydrocarbons intermediate said butane and said normally liquid hydrocarbon fractions and also to isomerize normal butane contained in said butane fraction, separating said iso-butane, transferring said iso-butane to an alkylation zone together with the fluorides which separate therewith from the averaging reaction, alkylating at least a part thereof with an olefin of not over 4 carbon atoms in the presence of the above defined catalyst comprising said fluorides separated from the averaging reaction, and separating said intermediate hydrocarbons and said alkylate in a single fractionating operation.

5. A process of producing hydrocarbons in the gasoline boiling range by processes of averaging and alkylating, which comprises subjecting a mixture of a normally liquid hydrocarbon fraction boiling in the gasoline-kerosene range, and a butane fraction containing normal butane, to the action of a liquid catalyst comprising liquid hydrogen fluoride in which is dissolved not over 50 mol per cent of boron trifluoride (based on the hydrogen fluoride), and continuing the reaction under averaging conditions including a pressure to maintain the hydrogen fluoride liquid and at a temperature and for a period of time while adjusting the partial pressure of the boron trifluoride to produce averaged hydrocarbons intermediate said butane and said normally liquid hydrocarbon fractions and also to isomerize normal butane contained in said butane fraction, separating said iso-butane, transferring said iso-butane to an alkylation zone together with the fluorides which separate therewith from the averaging reaction, alkylating said iso-butane with ethylene in the presence of the above-defined catalyst comprising said separated fluorides.

6. A process of producing hydrocarbons in the gasoline boiling range by processes of averaging and alkylating, which comprises subjecting a mixture of a normally liquid hydrocarbon fraction boiling in the gasoline-kerosene range, and a butane fraction containing normal butane, to the action of a liquid catalyst comprising liquid hydrogen fluoride in which is dissolved not over 50 mol per cent of boron trifluoride (based on the hydrogen fluoride), and continuing the reaction under averaging conditions including a pressure to maintain the hydrogen fluoride liquid and at a temperature and for a period of time while adjusting the partial pressure of the boron trifluoride to produce averaged hydrocarbons intermediate said butane and said normally liquid hydrocarbon fractions and also to isomerize normal butane contained in said butane fraction, separating said iso-butane, transferring said iso-butane to an alkylation zone together with the fluorides which separated therewith from the averaging reaction, alkylating said iso-butane with a butylene in the presence of the above-defined catalyst comprising said separated fluorides.

7. A process of producing hydrocarbons in the gasoline boiling range by processes of averaging and alkylating, which comprises subjecting a mixture of a normally liquid hydrocarbon fraction and a larger liquid volume of a normally gaseous hydrocarbon fraction containing a normal hydrocarbon, to the action of a liquid catalyst comprising liquid hydrogen fluoride in which is dissolved not over 50 mol per cent of boron trifluoride (based on the hydrogen fluoride), and continuing the reaction under averaging conditions including a pressure to maintain the hydrogen fluoride and the normally gaseous hydrocarbon fraction liquid and at a temperature and for a period of time while adjusting the partial pressure of the boron trifluoride to produce averaged hydrocarbons intermediate said normally gaseous and said normally liquid hydrocarbon fractions as a result of reactions which take place only in the presence of both said fractions, and also to isomerize the excess of the normal hydrocarbon contained in said normally gaseous fraction, separating the hydrocarbons as an upper layer from the major portion of the fluoride catalyst as a lower layer, separating the isomerized hydrocarbon from the upper layer together with the fluorides from the averaging reaction contained in said upper layer, and alkylating said isomerized hydrocarbons with an olefin in the presence of a catalyst comprising the fluorides separated from the averaging reaction.

8. A process of producing hydrocarbons in the gasoline boiling range by processes of averaging and alkylating, which comprises subjecting a mixture of a normally liquid hydrocarbon fraction boiling above the gasoline range, and a larger liquid volume of a normally gaseous hydrocarbon fraction containing normal butane, to the action of a liquid catalyst comprising liquid hydrogen fluoride in which is dissolved not over 50 mol per cent of boron trifluoride (based on the hydrogen fluoride), and continuing the reaction under averaging conditions including a pressure to

maintain the hydrogen fluoride and the normally gaseous hydrocarbon fraction liquid and at a temperature and for a period of time while adjusting the partial pressure of the boron trifluoride to produce averaged hydrocarbons intermediate said normally gaseous and said normally liquid hydrocarbon fractions as a result of reactions which take place only in the presence of both said fractions, and also to isomerize the excess of the normal butane contained in said normally gaseous fraction, separating the hydrocarbons as an upper layer from the major portion of the fluoride catalyst as a lower layer, separating the iso-butane from the upper layer together with the fluorides from the averaging reaction contained in said upper layer, and alkylating said isobutane with an olefin in the presence of a catalyst comprising the fluorides separated from the averaging reaction.

9. A process of producing hydrocarbons in the gasoline boiling range by processes of averaging and alkylating, which comprises subjecting a mixture of a normally liquid hydrocarbon fraction boiling above the gasoline range, and a larger liquid volume of a butane fraction containing normal butane, to the action of a liquid catalyst comprising liquid hydrogen fluoride in which is dissolved not over 50 mol per cent of boron trifluoride (based on the hydrogen fluoride), and continuing the reaction under averaging conditions including a pressure to maintain the hydrogen fluoride and the butane fraction liquid and at a temperature and for a period of time while adjusting the partial pressure of the boron trifluoride to produce averaged hydrocarbons intermediate said butane and said normally liquid hydrocarbon fractions as a result of the reactions which take place only in the presence of both said fractions, and also to isomerize the excess of the normal butane, separating the hydrocarbons as an upper layer from the major portion of the fluoride catalyst as a lower layer, separating the iso-butane from the upper layer together with the fluorides from the averaging reaction contained in said upper layer, and alkylating said iso-butane with an olefin in the presence of a catalyst comprising the fluorides separated from the averaging reaction.
